UNITED STATES PATENT OFFICE.

HUGO L. HILLER, OF NEW YORK, N. Y.

DESIGN FOR A SLIPPER-VAMP.

SPECIFICATION forming part of Design No. 18,384, dated June 12, 1888.

Application filed April 16, 1888. Serial No. 270,877. Term of patent 7 years.

To all whom it may concern:

Be it known that I, HUGO L. HILLER, of the city, county, and State of New York, have invented a new and original Design for Vamps, 5 of which the following is a specification.

The nature of my design is fully shown in the accompanying drawing, in which a face view of my newly-designed slipper-upper is shown.

10 The leading feature of my design consists in three crosses and ornamental lines between them.

15 A A represent three crosses grouped in proximity to each other on the outer surface of the front part of the upper.

B represents ornamental lines between the crosses and projecting over the upper crosses.

C represents ornamental lines below the bottom cross.

Having thus described my design, I claim as 20 new and desire to secure by Letters Patent—

The design for the surface configuration of a slipper-vamp, substantially as herein shown and described, the same consisting of a group of three crosses and ornamental lines between 25 and adjacent to the crosses, said group being arranged symmetrically in relation to the central line of the vamp.

In testimony that I claim the foregoing as my invention I have signed my name in presence of two subscribing witnesses.

HUGO L. HILLER.
